UNITED STATES PATENT OFFICE

HENRY E. CONKLIN, OF ROSLYN, NEW YORK

DESIGN FOR A BUILDING

Application filed January 27, 1932. Serial No. 42,635. Term of patent 14 years.

To all whom it may concern:

Be it known that I, HENRY E. CONKLIN, a citizen of the United States, residing at Roslyn, New York, have invented a new, original, and ornamental Design for a Building, of which the following is a specification, reference being had to the accompanying drawing, forming part thereof, which is an exte-

rior view of the building in bird's eye perspective, it being understood that the rear side of the building is substantially the same as shown in the drawing.

I claim,—

The ornamental design for a building as shown and described.

HENRY E. CONKLIN.
